US0D1113340S

(12) **United States Design Patent** (10) **Patent No.:** **US D1,113,340 S**
(45) **Date of Patent:** **** Feb. 17, 2026**

(54) **APPLIANCE**

(71) Applicant: **Sunbeam Products, Inc.**, Atlanta, GA (US)

(72) Inventors: **Bruce Arnold**, Portage, MI (US); **Rury Vizcarra**, Wyoming, MI (US); **Charlotte Zale**, University Heights, OH (US); **Chris Leyden**, Portage, MI (US)

(73) Assignee: **Sunbeam Products, Inc.**, Atlanta, GA (US)

(**) Term: **15 Years**

(21) Appl. No.: **29/912,421**

(22) Filed: **Sep. 19, 2023**

Related U.S. Application Data

(62) Division of application No. 29/783,995, filed on May 17, 2021, now Pat. No. Des. 1,003,644.
